(57) CLAIM

The ornamental design for a set of scrub brushes, as shown and described.

DESCRIPTION

FIG. 1 is a perspective view of a set of scrub brushes showing our new design.

FIG. 2 is a front view thereof.

FIG. 3 is a back view thereof.

FIG. 4 is a side view thereof.

FIG. 5 is another side view thereof.

FIG. 6 is a top view thereof; and,

FIG. 7 is bottom view thereof.

The broken lines showing the bristles and a brush back illustrate portions of the set of scrub brushes that form no part of the claimed design.
